UNITED STATES PATENT OFFICE

139,866

DESIGN FOR AN EMBOSSED LEATHER OR THE LIKE

Leonard I. Freedman, New York, N. Y.

Application September 29, 1944, Serial No. 115,526

Term of patent 7 years

(Cl. D87—3)

To all whom it may concern:

Be it known that I, Leonard I. Freedman, a citizen of the United States of America, residing in New York city, county of New York and State of New York, have invented a new, original, and ornamental Design for an Embossed Leather or the Like, of which the following is a specification, reference being had to the accompanying drawings, forming part thereof,

Fig. 1 is a plan view of an embossed leather or the like showing my new design. The design unit is contained between the dot and dash lines, which unit is repeated in regular succession as indicated by the extensions beyond the unit boundaries.

Fig. 2 is a detailed view on an enlarged scale of a portion of the leather shown in Fig. 1.

I claim:

The ornamental design for an embossed leather or the like, substantially as shown and described.

LEONARD I. FREEDMAN.
